UNITED STATES PATENT OFFICE.

JOHN LESTER GETMAN, OF HERKIMER, NEW YORK.

GAGE-PIN.

SPECIFICATION forming part of Letters Patent No. 437,687, dated October 7, 1890.

Application filed November 22, 1888. Serial No. 291,547. (No model.)

To all whom it may concern:

Be it known that I, JOHN LESTER GETMAN, of Herkimer, in the county of Herkimer and State of New York, have invented certain new and useful Improvements in Gage-Pins, of which the following is a specification.

My invention relates to gage-pins, and has reference particularly to that class of devices which are attached to or inserted into the tympan-sheets of the printing-press to hold the card or sheet to be printed in proper position to receive the impression.

The object of the invention is to produce a cheap, simple, and reliable gage-pin that can be used with the grippers without danger of injury to the form or to the gage-pins themselves. This result is accomplished by means of the construction shown in the drawings, in which—

20 Figure 1 is a perspective view of my improved gage-pin; Fig. 2, a similar view looking at the rear face of the pin, and Fig. 3 a view showing the pins in use.

A indicates the gage-pin as a whole, comprising a head B and an attaching-pin C, formed integral with the head, the said gage-pin being advisably cut or stamped from a piece of sheet steel or brass and suitably tempered and finished. The head B extends at 25 right angles to the pin C, so as to prevent the gage-pin as a whole from tipping laterally upon its attaching-pin C. This pin C is flat and made pointed at its lower end, and at a distance from the point it is provided with a 30 transverse bend, which tends to prevent the accidental withdrawal of the gage-pin.

D indicates a spring-arm formed integral with the head B and connected with either end thereof, the drawings showing the spring-arm as connected with the left-hand end of the head by a solid portion E, Figs. 1 and 2. This arm D at its free end, which projects beyond the end of the head B, curves upward slightly from the plane of the head, so as to 35 form a rest or support for the edge of the sheet or card to be printed, as will be understood upon reference to Fig. 3. In the edge

of the solid portion E is a notch or recess F, into which fits a tongue G, formed upon a detachable point H, as shown in Figs. 1 and 2, 50 the said point H being adapted to be inserted into or through the tympan-sheets after the gage-pin is placed in position to aid in securing the latter in proper position and preventing its shifting.

To further aid in retaining the gage-pin in place, I will advisably provide the head B and the corner of the solid portion E with pointed spurs I, which engage the tympan-sheets. From this construction it follows that if the 55 grippers strike the spring-arm D it will simply be pressed downward against the tympan-sheet, and when the grippers recede the arm will return to its normal position. The same action takes place in case any part of the 60 form should strike the arm.

That part of the arm D connected with the solid portion E is in the same plane with the latter and the head B, and consequently it will be impossible for the sheet or card to be 65 printed to fall down between the gage-pin and the tympan-sheet—a result that is further insured by the spur or point at the upper corner of the solid connecting portion E.

I am aware that, broadly considered, a gage- 70 pin having a spring-arm is not new, and, while not making any broad claim to a spring-arm *per se*, I believe that the construction herein shown and described is new with me and possesses advantages over those heretofore devised.

Having thus described my invention, what I claim is—

1. In a gage-pin, the combination, with the laterally-extending head B and pin C, of the 75 spring-arm D, connected with the head B by a solid portion E, extending in the same general direction with the head and curved outward away from the face of the head, as shown.

2. In a gage-pin, the combination, with the 80 head B and pin C, of the spring-arm D in the same plane with the head throughout a portion of its length, but curved outward away therefrom at its free end.

3. In a gage-pin, the combination, with the head B and pin C, of the spring-arm D, projecting from a portion E of the head, and a spur or point I, projecting rearwardly from the upper corner of the portion E.

4. In combination with a gage-pin, a detachable holding-point H, arranged and operating substantially as described.

5. In combination with a gage-pin provided

with socket or recess F, a detachable holding-point H, provided with a tongue G.

In witness whereof I hereunto set my hand in the presence of two witnesses.

JOHN LESTER GETMAN.
